STOVE CONTROL PANEL

Armour H. Titus, Jr., Galesburg, Ill.

Application May 13, 1955, Serial No. 35,978

Term of patent 14 years

(Cl. D81—4)

Fig. 1 is an elevational view of a stove control panel showing my new design;

Fig. 2 is a top plan view;

Fig. 3 is a side elevational view; and

Fig. 4 is a section on the line 4—4 of Fig. 1.

I claim:

The ornamental design for a stove control panel, as shown.
